UNITED STATES PATENT OFFICE.

ALBERT H. SCHERZER, OF CHICAGO, ILLINOIS.

BASCULE-BRIDGE.

1,114,535.

Specification of Letters Patent.

Patented Oct. 20, 1914.

Application filed March 3, 1913. Serial No. 751,733.

To all whom it may concern:

Be it known that I, ALBERT H. SCHERZER, a citizen of the United States, and a resident of Chicago, in the county of Cook and State of Illinois, have invented certain new and useful Improvements in Bascule-Bridges; and I do hereby declare that the following is a full, clear, and exact description thereof, reference being had to the accompanying drawings, and to the characters of reference marked thereon, which form a part of this specification.

This invention relates to improvements in bascule bridges of the rolling lift type, and refers more specifically to improvements in the tread portions of the curved segments or bearers upon which the bridge leaf rests and rolls and to the tracks by which said bridge is supported.

Among the objects of my invention is to provide an improved tread for the segments or bearers of such bridges, with a view to strengthening the tread sections thereof, and to provide means whereby sectional tread and track portions may be applied to the segments and track girders, respectively, in such a way as to be separately removable, and to thereby enable defective or injured tread or track sections to be removed and replaced by perfect ones.

The invention consists in the combination and arrangement of the parts hereinafter described and more specifically pointed out in the appended claims.

In the drawings:—Figure 1 is a partial side elevation of a rolling lift bridge leaf and one of its supporting track girders equipped with my invention, with some of the details omitted. Fig. 2 is an enlarged partial section and partial elevation of the bridge segment and track. Fig. 3 is a longitudinal section of two adjacent tread sections taken in a curved plane parallel to the bearing faces of said sections. Fig. 4 is a top plan view of a plurality of adjacent sections of the track. Fig. 5 is a side elevation of the latter, partially broken away. Figs. 6 and 7 are sections taken through the tread and track sections at two different vertical planes.

As shown in the drawings, 10 designates the shore end of a rolling lift bridge leaf, 11 one of the segments or bearers on which the leaf rests and rolls, 12 the counterweight for the leaf, and 13 one of the track girders

which supports the leaf. These parts, in themselves, may be made of any usual or preferred construction and need not be further described, excepting as to their relation to the features constituting the present invention.

The tread, designated as a whole by 14, is made up of a plurality of relatively short sections 15, which are preferably made of cast metal. Said sections may have curved bearing faces 16 that are adapted for rolling contact with the straight upper faces 17 of the track members or sections 18. The said bearing faces 16 and 17 of the tread and track sections are of relatively narrow transverse width, so that the load transmitted from the segments or bearers to the tracks is a concentrated load on parts of the tread and track sections which may be built sufficiently massive to support the load brought upon the same. Said bearing faces are thus also arranged in proper relation to the structure of the segments and girders to which they are applied. The said track sections 18 are herein shown as also made up of a plurality of the relatively short sections or members which are attached to the webs 20, 20 of the track girders.

As herein shown the tread sections 15 of the bridge leaf segments are of hollow construction and comprise central or intermediate bearing portions 20', on the lower faces of which are formed the bearing faces 16, and parallel walls 21, 21 which extend upwardly or outwardly therefrom and are provided at their upper margins with lateral flanges 22, 22. When the tread sections are applied to a two web segment, the webs 24, 24 thereof are arranged in the planes of the flanged walls 21, 21 of the tread sections, and said tread sections are removably attached to the webs through the medium of angle bars 25, the webs of which overlap and are riveted or bolted to the webs of the bridge segments, and the flanges of which overlap and are attached to the lateral flanges 22 of the track sections, as by means of the bolts 26. The marginal portions of the webs 24 may be further reinforced, as by the plates 24' applied to the inner face of the web 24 and riveted or bolted thereto, to provide the proper strength at this point, as shown in Figs. 6 and 7. The said tread sections are provided at their ends with lateral flanges 28, which, in the assembled

positions of the sections on the tread, abut against each other, and said flanges are apertured to receive bolts 30 by which the tread sections are attached together end to end. This construction provides means for connecting the separately applied tread sections to the segment in such manner as to constitute a practically continuous or one-piece tread, when the parts are assembled and fastened together, while permitting said tread sections to be separately removed and replaced when required.

The track sections 18 may be constructed and applied to the track girder 13 in a generally similar manner as are the tread sections above described, and as more clearly shown in Figs. 2, 6 and 7. Said track sections also fit together at their ends and are fastened together by means of the bolts 32 which extend through lateral flanges 33 of the adjoining ends of the track sections. They comprise the central or bearing portion 34 on which are formed the bearing faces 17 and the side walls 34' which are flanged at their lower margins and are attached to the webs 20 by angle bars 34².

From an inspection of Fig. 6, it will be noted that the bearing or engaging faces of the tread and track sections are relatively narrow and principally within the width of the flanges or walls 21, 34' of said tread and track sections, respectively, so that thereby the load is concentrated on relatively narrow portions of the tread and track sections, which are built sufficiently massive to support the load. The flanges 28 and 33, of the tread and track sections, respectively, terminate short of the bearing faces of said sections, as most clearly shown in Fig. 6, and the bearing faces terminate at their margins slightly short of the planes of the walls 21 and 34', so that said latter flanges and the extreme side marginal portions of the bodies of the sections do not bear upon each other. This is an advantage, inasmuch as if a substantial load be transmitted through a relatively thin or weak unreinforced portion of the track and tread sections by reason of lateral pressure due to uneven loading or tendency to twisting of the bridge leaf on the tracks, there would be a tendency to break such lateral unreinforced portions.

In Figs. 3, 4 and 6, I have shown the tread and track sections as provided with transverse end walls that are formed to provide tongues 35, 36 respectively, which enter corresponding notches 37, 38 of the tread and track sections, respectively. This construction provides continuous bearing surfaces between adjacent sections, and also aids to hold the interlocked sections laterally in line and prevent a tendency to displacement thereof under unequal lateral loading stresses. The said tread and track sections are provided laterally outside of

the bearing faces thereof with interlocking teeth or racks which prevent displacement of the tread relatively to the tracks in a line parallel to the tracks. As herein shown, the track sections are provided at their lateral margins and outside of their bearing faces with upstanding teeth 40, and the tread sections are provided in line therewith with separated lugs 41 between which are formed notches 42 into which the teeth 40 engage. These teeth and notches are reinforced or strengthened by fillets 43, 44 as best shown in Fig. 7. The arrangement shown constitutes an exceedingly simple and effective means of providing an interlocking connection between the tread and track sections, without limiting in any way the capacity of the load transmitting bearings between said parts, or interfering with the bearing faces of the tread and track sections.

The structural details are capable of some variation within the spirit and scope of the invention, and the invention is not limited to the precise details shown except as hereinafter made the subject of specific claims and as imposed by the prior art.

I claim as my invention:—

1. A rolling lift bridge comprising a leaf adapted to rest and roll on a support, and a tread comprising tread sections attached to the leaf and having laterally fixed interlocking engagement with each other.

2. A rolling lift bridge comprising a leaf adapted to rest and roll on a support, and a tread comprising tread sections removably attached to the leaf and overlapping means connecting the adjoining ends of said tread sections and extending longitudinally thereof to constitute a continuous tread and laterally interlocked to hold the tread sections laterally fixed with respect to each other.

3. A rolling lift bridge comprising a leaf adapted to rest and roll on a support, and a tread therefor comprising a plurality of removably applied tread sections provided at their ends with tongue and notch connections, for the purpose set forth.

4. A rolling lift bridge comprising a leaf adapted to rest and roll on a support and a tread comprising tread sections having means to removably attach them to said leaf, said means to attach said sections to said leaf comprising laterally extending flanges on said tread sections, like flanges on the leaf and means extending through said flanges to fasten said tread sections to said leaf.

5. A rolling lift bridge comprising, in combination with a leaf and a two-web segment through the medium of which the leaf is supported, of tread sections having bearing faces for contact with a support and side walls in line with the webs of said segment and having means to removably attach the same to said segment.

6. A rolling lift bridge comprising, in combination with a leaf and a two web segment through the medium of which the leaf is supported, of tread sections having bearing faces for contact with a support, said tread sections having radial flanges in line with the webs of said segment, said radial flanges and the webs having lateral flanges which engage each other, and fastening 5 means extending through said latter flanges.

7. A rolling lift bridge comprising, in combination with a leaf and a two web segment through the medium of which the leaf is supported, of tread sections having bearing faces for contact with a support and side walls in line with the webs of said segment and having means to removably attach same to said segment, said bearing faces being solid or unbroken and fixed locking 15 projections on said tread sections laterally exterior to said bearing faces.

8. A rolling lift bridge comprising a leaf provided with supporting segments, and tread sections therefor comprising curved bearing faces and walls having means to attach them to said segments, and flanges on said tread sections laterally exterior to said bearing faces having fastening means extending therethrough, said lateral flanges terminating short of the bearing faces of 25 said tread sections.

9. A rolling lift bridge comprising a leaf provided with supporting segments, and tread sections therefor comprising curved bearing faces and walls having means to attach them to said segments and flanges on 35 said tread sections laterally exterior to said bearing faces having fastening means extending therethrough, said lateral flanges terminating short of the bearing faces of 40 said tread sections, and the ends of said

tread sections having laterally interlocking tongue and groove connection.

10. A rolling lift bridge comprising a leaf adapted to rest and roll on a support, 45 and a tread comprising tread sections attached to the leaf and having longitudinally overlapping laterally fixed interlocking engagement with each other at their ends, combined with a supporting girder provided 50 with removably attached tread sections having like overlapping engagement with each other.

11. In a rolling lift bridge, a supporting two-web girder for the bridge and a 55 removable sectional track thereon provided with an upwardly facing bearing face and with walls in line with the webs of the girder, and at the lower sides of the walls with lateral flanges, lateral flanges on the 60 girder webs, and bolts extending through said flanges.

12. In a rolling lift bridge, a supporting two-web girder for the bridge and a removable sectional track thereon provided with 65 an upwardly facing bearing face and with walls in line with the webs of the girder, and at the lower edges of the walls with lateral flanges, lateral flanges on the girder webs, fastening bolts extending through 70 said flanges and locking teeth or projections on said sections arranged laterally outside of said bearing faces.

In testimony, that I claim the foregoing as my invention I affix my signature in the 75 presence of two witnesses, this 1st day of March, A. D. 1913.

ALBERT H. SCHERZER.
